UNITED STATES PATENT OFFICE.

LOUIS L. PRATT, OF PHILADELPHIA, PENNSYLVANIA.

ROTARY PUMP.

No. 897,655.

Specification of Letters Patent.

Patented Sept. 1, 1908.

Application filed December 9, 1907. Serial No. 405,647.

To all whom it may concern:

Be it known that I, LOUIS L. PRATT, a citizen of the United States, residing in the city and county of Philadelphia, State of Pennsylvania, have invented a new and useful Rotary Pump, of which the following is a specification.

My invention relates to an improvement in a rotary pump and consists of a series of buckets and means for throwing the same into operative and inoperative positions and respectively retaining them in the same.

It further consists of a rotary device adapted to carry said buckets, the same being of novel construction, as will be herein-after described.

For the purpose of explaining my invention, the accompanying drawings illustrate a satisfactory reduction of the same to practice, but the important instrumentalities thereof may be varied, and so it is to be understood that the invention is not limited to the specific arrangement and organization shown and described.

25 Figure 1 represents a section on line $x-x$, Fig. 2, of a pump embodying the invention. Fig. 2 represents a section thereof on line $y-y$, Fig. 1. Fig. 3 represents a perspective view of a detached portion thereof.

30 Similar letters of reference indicate corresponding parts in the figures.

In the drawings:—1 designates a casing, which is provided with stuffing boxes 2, in which latter is mounted the driving shaft 3.

35 4 designates a drum, which is located within the casing and composed of the side heads 5 and 6, the cross-bars 7, which connect the same, and the hub 8, which is secured to the head 5 and occupies the center 40 of the drum, it being noticed that the head 6 is open or of the form of an annulus, and that the shaft 3 passes through the hub 8 and is keyed or otherwise secured thereto.

In the heads 5 and 6 are transversely-extending openings forming bearings 9 for the gudgeons 10 of swinging buckets 11, which occupy positions between said heads, one of the portions of each bucket having a shoulder 12 thereon, which when the buckets are 50 closed, abuts against a shoulder 13 on the adjacent cross-bars 7, thus limiting the closing motion of the buckets, it being also noticed that the other portion of the bucket, when the latter is in open or operative position, is adapted to abut against the hub 8, so as to be firmly sustained, while also being

limited in its opening motion, and that the last named portion is made lighter than the other portion, so that the bucket will swing by gravity to its operative position, as shown 60 at the bottom of Fig. 1. The hub 8 forms a common stop for all of the buckets when in their operative positions. Each pair of the gudgeons 10 is connected with the respective bucket intermediate of the ends of the latter, 65 so that the strain of the water on the bucket in lifting the same is equalized from end to end of the bucket.

Secured to the side of the casing and to the head 6, is the abutment 14, which extends 70 through the opening of said head into the casing and around the hub 8 and has a cam face 15, which is eccentric to the axis of the drum, said face being adapted to form a rolling contact for the lighter end of the 75 bucket, the remaining face of said abutment being concentric to said axis.

Secured to the interior of the circumferential wall of the casing, is the abutment 16, which projects into the peripheral portion of 80 the drum between the heads 5 and 6, and has part of its inner face of the form of a cam 17, which is eccentric to the axis of the drum, and another portion 18 concentric with said axis.

85 The casing is provided respectively with an inlet 19 and outlet 20 for evident purposes.

The operation is as follows:—Power is applied to the shaft 3 to rotate the same, and consequently the drum, whereby the buckets are carried around with said drum. When a bucket is in the position shown at the bottom of Fig. 1, it is taking water, and the latter is raised through the casing and discharged 95 through the outlet 20. Then the bucket is carried towards the abutment 14, and when its lighter or inner portion reaches the cam face 15 of the abutment 14, it rolls on the same and so is positively turned towards a 100 closing position, as shown by the upper bucket in Fig. 1. Then the bucket owing to the position of its heavier portion, fully closes by gravity towards the body of the cam 14, this being permitted by the eccentric portion or cam 17 of the abutment 16, said portion now abutting against the adjacent cross-bar 7, and so being properly controlled against further closing motion as it moves through the passage between the concentric faces of the 105 abutments 14 and 16, as shown at the left side of Fig. 1. Then the bucket lowers, and 110

and as it clears the terminal of the abutment 16, it turns on its axis and reassumes its first position, one portion turning from its abutment 7, and the other portion turning towards 5 the hub 8, with which latter it abuts, when it is again operative, as shown at the bottom of Fig. 1.

Having thus described my invention, what I claim as new and desire to secure by Letters 10 Patent, is:—

1. In a rotary pump, a casing, a rotatable drum therein, a shaft-receiving hub centrally in said drum rotatably-connected therewith, a bucket mounted within said drum, 15 and a transversely-extending connection for the heads of said drum, said hub and connection forming stops for the opposite ends of said bucket in the rotation of the latter with the drum which carries the same.
2. In a rotary pump, a casing, an inlet and an outlet therefor, a drum in said casing, a bucket pivoted intermediate of its ends to said drum, means within the periphery of said drum for causing said bucket to swing 25 in one direction and means within the periphery of said drum whereby said bucket swings by gravity in the opposite direction said drum being provided with a plurality of stops respectively for the opposite ends of 30 said buckets.
3. In a rotary pump, a casing, an inlet and an outlet therefor, a drum in said casing, a shaft-receiving hub on said drum and rotatable therewith, buckets pivoted to said 35 drum, means within the periphery of said drum outside said hub for engaging said buckets and causing them to swing in one direction, and means within the periphery of said drum whereby said buckets swing by 40 gravity in the opposite direction, said hub forming a common stop for said buckets for engagement with one end of the latter, and means on the drum serving as stops for the other ends of said buckets.
4. In a rotary pump, a casing, an inlet and 45

an outlet therefor, a drum in said casing, buckets pivoted to said drum, means whereby said buckets swing by gravity in one direction, a common stop for said buckets, means for causing said buckets to swing in 50 the opposite direction, and a stop for the buckets in the path of travel of said buckets.

5. In a rotary pump, a casing, an inlet and an outlet therefor, a drum in said casing, buckets pivoted to said drum, stops adapted 55 for the opposite ends of said buckets, and means to overturn said buckets.

6. In a rotary pump, a casing, an inlet and an outlet therefor, a drum in said casing, a head forming one side of said drum, an annulus forming the other side thereof, a bucket pivoted between said head and annulus, means to oscillate said bucket, a stop to limit such oscillation in one direction, and connections for said head and ring forming stops in 65 the other direction.

7. In a rotary pump, a casing, an inlet and an outlet therefor, a drum in said casing, a head forming one side of said drum, an annulus forming the other side thereof, buckets 70 pivoted between said head and annulus, means adapted to swing said buckets to operative position, a cam adapted to swing said buckets to inoperative position, a stop on said drum common to said buckets in operative 75 position, and stops on the buckets and drum adapted to interlock for holding the buckets in inoperative position.

8. In a rotary pump, a bucket carrying drum composed of side heads, a hub centrally 80 on one of said heads, and connections for said heads, the other head being of the form of an annulus, said hub and connections forming stops for the bucket respectively in its operative and inoperative positions.

LOUIS L. PRATT.
